CLAIM

The ornamental design for a covered container for mail or the like, substantially as shown and described.

DESCRIPTION

FIG. 1 is a top perspective view of a covered container for mail or the like showing our new design;

FIG. 2 is a top plan view;

FIG. 3 is a side elevational view the opposite side being the same in appearance;

FIG. 4 is an end elevational view the opposite end end being the same in appearance;

FIG. 5 is a bottom plan view; and

FIG. 6 is an exploded top perspective view thereof.
